UNITED STATES PATENT OFFICE.

JAMES H. McGLYNN AND WILLIAM P. HOWELLS, OF WILKES-BARRÉ,
PENNSYLVANIA.

CLOCK-ALARM.

SPECIFICATION forming part of Letters Patent No. 375,497, dated December 27, 1887.

Application filed May 16, 1887. Serial No. 238,397. (No model.)

To all whom it may concern:

Be it known that we, JAMES H. McGLYNN and WILLIAM P. HOWELLS, of Wilkes-Barré, in the county of Luzerne and State of Pennsylvania, have invented a new and useful Improvement in Alarm Attachments for Clocks, of which the following is a full, clear, and exact description.

This invention consists in what may be termed a "silent alarm" or "arousing attachment" to clocks of different kinds for calling or waking a person at any time required, ranging, say, from five minutes to twelve hours from the time the alarm is set, without disturbing others by the noise of the alarm, and without interfering with the clock-movement or retarding its speed, and whereby the greatest facility is afforded for setting the alarm, substantially as hereinafter described, and pointed out in the claims.

Reference is to be had to the accompanying drawings, forming a part of this specification, in which similar letters of reference indicate corresponding parts in both the figures.

Figure 1 represents a view in elevation of an alarm attachment as applied to the back of a clock or time-piece and as embodying our invention; and Fig. 2 is a partly-sectional plan view of the same, the section being taken upon the line *xx* in Fig. 1.

A is a clock or stationary time-piece of any suitable kind, and *b* a pinion on the hour-spindle of the same, which pinion may be on the exterior of the back of the clock, as here shown, or elsewhere.

B is a spur-gear of, say, twelve times the size of the pinion, into which said pinion meshes. This wheel is divided on its face into twelve equal parts, representing the several hours of the day or night, and these parts subdivided into other equal parts representing minutes. Upon the face of said wheel *B* is a stud or pin, *c*, which, as it comes round in a given or set space of time, strikes an approximately upright lever, *C*, and liberates an approximately horizontal lever, *D*, on which it catches or with which it engages. This lever *D* has connected with it, as by a cord or chain, *E*, arranged to pass over an elevated pulley, *F*, a weight, *G*, of any required size or capacity, and as the

lever *D* is liberated from the lever *C* said weight descends to give the alarm or desired arousing effect—as, for instance, by pulling through the cord or chain *E* on the person of the party using the alarm, or in any other desired manner. To this end the cord or chain *E* is suitably extended beyond the lever *D*, and said cord or chain made to engage with the lever *D* by a ring or loop, *e*, that on the disengagement of the lever *D* from the catch or tripping lever *C* slips off or from the lever *D* in order to allow the weight *G* to descend. Said ring also serves another purpose or function—that is to say, on being liberated from the lever *D* it acts as a stop to prevent the weight *G* from striking the floor by said ring coming in contact with the hanger *I* of the pulley *F* or other obstruction before the weight can reach the floor, thus doing away with any disturbing noise to others in the house.

To set or change the "alarm," the wheel *B* is turned so as to bring the stud *c* at a greater or less distance in the forward travel of said wheel from its contact-point with the lever *C*, according to the time the alarm is required to act. To do this it will be necessary to provide for turning the wheel *B* both back and forth without disturbing the clock-movement. This we accomplish as follows: The wheel *B* is hung so as not only to be free to turn upon a fixed stud, *f*, but also to be slid longitudinally thereon when required, so as to put it out of gear, as shown by dotted lines in Fig. 2, with the pinion *b*, when turning said wheel to adjust or set the alarm. This wheel *B* is provided with an enlarged sleeve, *g*, which not only receives the stud *f* within it, but also a spiral spring, *h*, that bears at its outer end against a stop on the outer end of the stud *f* and at its inner end against the wheel. This spring operates to force the wheel *B* into and to hold it in gear with the pinion *b*, excepting when said wheel is purposely drawn out from gear therewith, as described.

The alarm attachment runs free and easy, so that it has little or no perceptible effect upon the time-movement of the clock.

Having thus fully described our invention, we claim as new and desire to secure by Letters Patent—

1. In an alarm attachment for clocks, the combination, with the pinion of the clock-movement, of the spur-wheel having time-divisions upon it and provided with an alarm-operating stud or pin, the tripping-lever, an additional lever engaging with said tripping-lever, and the pulley and the cord or flexible connection, to one end of which is attached a weight, and which is adapted for attachment to the person to be roused, and provided with a ring or loop engaging said additional lever and having contact with said pulley, substantially as set forth.

2. In an alarm attachment for clocks, the combination, with the pinion *b* of the clock, of the stud *f*, the spring *h*, and the operating adjustable wheel *B* of the alarm attachment having a sleeve, *g*, and adapted to rotate upon said stud with freedom to slide thereon subject to control by the spring, substantially as and for the purposes herein set forth.

JAMES H. McGLYNN.

WILLIAM P. HOWELLS.
